UNITED STATES PATENT OFFICE.

ANTON J. HAUG, OF NASHUA, NEW HAMPSHIRE, ASSIGNOR TO IMPROVED PAPER MACHINERY COMPANY, OF NASHUA, NEW HAMPSHIRE, A CORPORATION OF MAINE.

SEPARATOR AND CONVEYER FOR PAPER-PULP MACHINERY AND OTHER PURPOSES.

1,266,257.

Specification of Letters Patent. Patented May 14, 1918.

Application filed October 11, 1915. Serial No. 55,164.

To all whom it may concern:

Be it known that I, ANTON J. HAUG, a citizen of the United States, and a resident of Nashua, county of Hillsborough, State 5 of New Hampshire, have invented an Improvement in Separators and Conveyers for Paper-Pulp Machinery and other Purposes, of which the following description, in connection with the accompanying drawings, is 10 a specification, like characters on the drawings representing like parts.

This invention relates to separators and conveyers peculiarly adapted for use in paper pulp machinery, but which may be 15 used in other relations.

In order that the principle of the invention may be readily understood, I have in the accompanying drawings disclosed a single embodiment of my invention and representing two uses to which among others 20 the same may be applied.

In the drawings:

Figure 1 is a plan view of a separator and conveyer embodying my invention and 25 adapted for use in connection with paper pulp machinery;

Fig. 2 is a longitudinal section of the separator and conveyer shown in Fig. 1;

Fig. 3 is a view in vertical transverse section showing the application of my invention to a sewerage filter; and

Fig. 4 is a view partially in plan and partially in horizontal section of the apparatus shown in Fig. 3.

35 The separator and conveyer herein disclosed is particularly adapted for use in connection with any moving body and particularly with a moving body of a screen-like nature and adapted to receive thereon 40 wet or moistened material, the solid or semi-solid portions of which are to be separated and conveyed to some other point. My invention is therefore peculiarly useful in the handling of paper pulp and like materials.

45 Heretofore so far as I am aware it has been customary to strip or remove paper pulp from a rotating screen by the use of a suction fan or like device directly connected with a conduit, the entrance whereof is in 50 proximity to the screen, whereby the paper pulp is sucked or drawn through the conduit and through the fan or other suction

device. This is highly objectionable, resulting in the clogging of the suction device. Such clogging results to a detrimental extent even 55 though a receptacle be provided between the screen and the fan for the purpose of receiving, through the action of gravity, the paper pulp. Inasmuch as such receptacle is of necessity directly connected with the fan 60 or other suction device, more or less of the paper pulp is drawn by suction past such receptacle and into the fan. One important object of my invention is to avoid such clogging. Other objects of the invention 65 will be set forth more fully hereinafter.

In Figs. 1 and 2, I have represented one use of my invention wherein the same is employed as a compressed fluid conductor for paper pulp. Therein the rotating screen 70 of a paper pulp apparatus is diagrammatically indicated at 1, it being mounted in any suitable or usual manner for rotation. In operative relation thereto I mount a casing 2 formed of metal or other suitable material, 75 and preferably of substantially the entire length of the screen 1. The said casing constitutes a conduit and is provided with a relatively narrow throat or entrance 3, here shown as downwardly directed and positioned in proximity to the screen 1, so that it may receive material therefrom. Integrally formed with or suitably attached to the casing 2 is a nozzle or discharge portion 4 of the said conduit, it being preferably 80 of the same length as said casing 2, so as to permit the effective discharge of material therefrom.

The left hand end of the casing 2, viewing Fig. 2, is connected with some suitable 90 source of fluid under pressure, as, for example, compressed air, whereby the air under pressure enters the said casing in the direction of the arrow and is discharged therefrom through the flattened nozzle 4 to 95 any suitable point. If desired and preferably the material may be discharged into some suitable storage receptacle or may be conveyed to some other portion of the paper machinery for further manipulation.

100 The throat 3 has formed therewith or is in direct communication with an inner pipe or conduit 5, herein represented as suitably mounted within an inwardly extending por-

tion 6 of said throat. The conduit 5 extends in the same direction as the nozzle 4 and is preferably flattened and of a width substantially equaling the length of the screen 1, so that the paper pulp may be readily conveyed therethrough. The said conduit 5 terminates at some suitable point within the nozzle 4.

The throat 3, pipe 5 and nozzle 4 constitute a materials conduit, and the throat or entrance end of the conduit preferably has its wall which is opposed to the on-coming, moistened, semi-solid material, so inclined or related to the materials-carrying surface that the material as delivered to that wall and diverted from the surface, can be made readily to slide along into the materials conduit.

Preferably there is also provided means for directing against the materials received on the wall, a high velocity current of air to drive them along the wall and the conduit. While this action may be secured in other ways, herein such provision is had by an ample clearance space between the mouth of the throat and the material on the screen, so that the air has free access to the throat between the material and the lip or lips of the mouth. The high velocity air entering the mouth about its edges under the suction created within the conduit strikes the semi-solid material delivered to the throat and through its impact against the same forces or impels it along the conduit. It is not essential that the air which creates the suction at the mouth and the pressure at the discharge end of the conduit be forced into the latter at any particular point therein so long as the fan, blower or other source of pressure is external or out of the path of the materials and the air pressure is directed toward the discharge end to discharge the materials by the force of pressure behind them and at the same time create a drawing-in suction effect at the mouth of the conduit.

While the air clearance space, if desired, might be provided to an equal degree between all edges of the mouth and the material on the screen, preferably the edge of the mouth which is formed by the wall on which the material is received (the lower edge in Fig. 2) is brought into relatively close relation to the screen while there is provided a relatively greater air clearance space between the opposite edge of the mouth and the material on the screen. By this arrangement the mechanical impact of the current of high velocity air drawn in the mouth is added to the lifting effect of the suction on the pulp or other moist material. This air strikes the partly lifted semi-solid material as it tends to pile up on the wall of the throat and to drive it along that wall into the conduit. To this there is also added the mechanical effect of the

rotation of the screen which tends to drive the material along the inclined wall of the throat.

The opposed wall of the throat on which the material is received constitutes, in effect, stripping means, for in conjunction with the suction and the impact of the air, it acts to receive and divert the layer of moistened material from the screen or other surface, although alone and of itself it may, and preferably does, have little or no mechanical stripping action, its edge being preferably, though not necessarily, located away from and out of contact with the traveling materials-carrying surface.

In Figs. 3 and 4, I have represented another use for my invention but involving the employment of a screen adapted to receive the wet or moistened material.

In said figures, I have represented a disk-like screen 7 fast upon a shaft 8 having thereon a worm wheel 9 adapted to be driven by a worm 10 in any suitable manner, not herein necessary more fully to disclose. The said screen 7 is adapted to receive sewerage material thereon entering through the conduit 11. I have herein represented the screen 7 as mounted upon an inclined axis, but my invention is not limited to such construction.

Coöperating with the upper surface of the disk screen 7 is a box or casing 12 of suitable extent, it being shown in Fig. 3 as of a length substantially equaling the radius of the screen 7. The said box or casing 12 is connected by the inlet pipe 13 to any suitable source of fluid under pressure and preferably compressed air. I have herein represented the inlet pipe 13 as bifurcated, being connected to the box or casing 12 at the points 14, 15.

The box or casing 12 is provided with an in-take throat 16 positioned in close proximity to the surface of the screen 7 and extending within the box or casing 12 to a suitable point, as indicated at 17 in Fig. 4. The box or casing 12 constituting a portion of a main conduit is provided with a suitable discharge portion 18, herein represented as of conical form and itself communicating with the ultimate discharge 19. Preferably the extension 17 of the throat 16 extends into the portion 18 of the box or casing 12. The construction and relation of parts are such that the air under pressure entering the box or casing 12 from the inlet pipe 13 and passing into the outlet 19, draws or sucks the solid or semi-solid material from the screen 7 in a manner analogous to that already set forth in connection with the form of my invention shown in Figs. 1 and 2.

While I have represented my invention as applied to two different uses and while my invention may be employed in other relations, I desire it to be understood that it is

peculiarly adapted for use in cases where material of a more or less solid nature is designed to be separated from the liquid or where stock is to be saved from waste material. Therefore the invention is peculiarly adapted for use in paper or paper pulp manufacture, and wherein the compressed fluid ductor coöperates with a cylinder rotating through waste material, whereby such 5 ductor draws off the available material and in such manner as if desired to conduct it back to the source of supply. I have not in Figs. 1 and 2 represented the system to which the ductor or separator and conveyer 10 is designed to be connected, inasmuch as the same may be of the usual construction. It is, however, to be understood that the separated material may be conveyed from the discharge nozzle 4 back to the source of 15 supply.

Having thus described one illustrative embodiment of my invention, I desire it to be understood that although specific terms are employed, they are used in a generic and 20 descriptive sense and not for purposes of limitation, the scope of the invention being set forth in the following claims.

Claims—

1. An apparatus for handling moistened, 30 semi-solid material presenting a traveling surface adapted to receive and carry moistened material, and a separator and conveyer combined therewith for separating material from said surface and conveying the same to a suitable receptacle and comprising a materials conduit having an entrance end for the semi-solid material and a discharge end, together with means for discharging fluid under pressure from a suitable external 35 source into said materials conduit toward the discharge end to create a suction at the entrance end and discharge the materials by pressure behind them at the discharge end, said entrance end presenting to the materials-carrying surface an entrance mouth extending transversely the surface for substantially the full extent thereof and having an opposed stripper wall, the edge of which is in close proximity to said surface, said 40 stripper wall being adapted to receive the layer of material as it is lifted from said surface and divert it toward the discharge end of the conduit, there being sufficient clearance between said entrance mouth and the material on the traveling surface to admit of the free entrance of air to said conduit between the material and the mouth to provide for directing against the materials received by the stripper wall a high velocity 45 current of air to drive the same along said wall to the conduit.

2. An apparatus for handling moistened, 50 semi-solid material presenting a traveling surface adapted to receive and carry moistened material, and a separator and conveyer combined therewith for separating the material from said surface and conveying the same to a suitable receptacle and comprising a materials conduit having an entrance end for the semi-solid material and a discharge end, together with means for discharging fluid under pressure from a suitable external 55 source into said materials conduit toward the discharge end to create a suction at the entrance end and discharge the materials by pressure behind them at the discharge end, said entrance end presenting to the materials-carrying surface an entrance mouth extending transversely the surface, said mouth having a stripper wall presented to the oncoming material, the edge of which is in close proximity to said surface, and having provision for directing against the materials received by the stripper wall a high velocity 60 current of air to drive the materials along said wall to the conduit, the entrance end of said conduit being of relatively less cross-sectional area than the discharge end thereof.

3. An apparatus for handling moistened, 65 semi-solid material presenting a traveling

surface adapted to receive and carry moistened material, and a separator and conveyer combined therewith for separating material from said surface and conveying the same to a suitable receptacle, and comprising a materials conduit having an entrance end for the semi-solid material and a discharge end, together with means for discharging fluid under pressure from a suitable external 70 source into said materials conduit toward the discharge end to create a suction at the entrance end and discharge the materials by pressure behind them at the discharge end, said entrance end presenting to the materials-carrying surface an entrance mouth extending transversely the surface and having an opposed stripper wall, the edge of which is in close proximity to said surface, said stripper wall being adapted to receive the layer of material as it is lifted from said 75 surface and divert it toward the discharge end of the conduit, there being sufficient clearance between said entrance mouth and the material on the traveling surface to admit of the free entrance of air to said conduit between the material and the mouth to provide for directing against the materials received by the stripper wall a high velocity 80 current of air to drive the same along said wall to the conduit.

4. An apparatus for handling moistened, 90 semi-solid material, embodying a materials-carrying member adapted to receive and carry the moistened material upon its surface, and a separator and conveyer combined therewith for separating the material from said surface and conveying the same to a suitable receptacle and comprising a materials conduit having an entrance end for the semi-solid material and a discharge end, together with means for discharging fluid under pressure from a suitable external 95 source into said materials conduit toward the discharge end to create a suction at the entrance end and discharge the materials by pressure behind them at the discharge end, said entrance end presenting to the materials-carrying surface an entrance mouth extending transversely the surface, said mouth having a stripper wall presented to the oncoming material, the edge of which is in close proximity to said surface, and having provision for directing against the materials received by the stripper wall a high velocity 100 current of air to drive the materials along said wall to the conduit, the entrance end of said conduit being of relatively less cross-sectional area than the discharge end thereof.

5. An apparatus for handling moistened, 105 semi-solid material, embodying a materials-carrying member adapted to receive and carry the moistened material upon its surface, and a separator and conveyer combined therewith for separating the material from said surface and conveying the same to a suitable receptacle and comprising a materials conduit having an entrance end for the 110

semi-solid material and a discharge end, together with means for discharging fluid under pressure from a suitable source into said materials conduit toward the discharge end to create a suction at the entrance end and discharge the materials by pressure behind them at the discharge end, said entrance end presenting to the materials-carrying surface an entrance mouth extending transversely the surface, said surface and entrance mouth being relatively movable to present successive portions of the material to the latter, said mouth having a stripper wall directed toward said surface and opposed to the direction of movement thereof, said wall terminating in an edge in close proximity to said surface, and said mouth having an opposite edge located farther away from the surface of the materials-carrying member than the stripper wall, whereby successive portions of the material presented to said entrance mouth may be separated from the surface and conveyed into the mouth and along the opposite wall of the conduit by the impact of the high

velocity air entering the clearance space around said mouth and acting against the separated materials.

5. The combination with a traveling member adapted to carry upon its surface semi-solid material in sheet form, of a suction conduit for moving the material therefrom, said conduit having a mouth extending transversely said surface and said mouth having a stripper wall directed toward said surface and opposed to the direction of movement of the adjacent surface with a materials-receiving edge in close proximity to the surface to divert material therefrom and having an opposite edge located farther away from said materials-carrying surface than said materials-receiving edge.

In testimony whereof, I have signed my name to this specification in the presence of two subscribing witnesses.

ANTON J. HAUG.
